UNITED STATES PATENT OFFICE.

DAVID D. GORDON, OF CHICAGO, ILLINOIS, ASSIGNOR TO THE YOST ELECTRIC MANUFACTURING COMPANY, OF TOLEDO, OHIO, A CORPORATION OF OHIO.

ELECTRIC-SWITCH MECHANISM.

1,220,220.

Specification of Letters Patent. Patented Mar. 27, 1917.

Application filed November 8, 1915. Serial No. 60,014.

To all whom it may concern:

Be it known that I, DAVID D. GORDON, a citizen of the United States, and a resident of Chicago, in the county of Cook and State 5 of Illinois, have invented a certain new and useful Electric-Switch Mechanism; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 My invention relates to electric switching devices of the quick make and break type, and particularly to switches of this character intended for use in electric lamp sockets or the like.

20 The object of my invention is the provision of an improved electric switching mechanism of the class described which is compact in form, simple, durable and inexpensive in its construction, and highly efficient in its operation, whereby to enhance the practicability and commercial value of 25 mechanisms of this character. My switch is also capable of being easily and quickly assembled which adds to its commercial 30 value.

The invention is fully described in the following specification, and while, in its broader aspect, it is capable of embodiment in numerous forms, a preferred and several 35 modified embodiments thereof are illustrated in the accompanying drawings, in which,—

Figure 1 is a central longitudinal section of a socket embodying the preferred form 40 of my switch, with parts of the switch in full. Fig. 2 is an inner end view of the socket with the cap members of the shell and interior insulating body removed. Fig. 3 is a section on the line X in Fig. 2. Fig. 4 is a view of the outer or lamp attaching end 45 of the socket. Fig. 5 is a perspective view of the bridging member of the switch. Fig. 6 is a sectional view of the switch mechanism separated from the socket. Fig. 7 is a 50 central longitudinal section of a socket embodying a modified form of my switching mechanism. Fig. 8 is an inner end view thereof with the cap members of the shell and interior insulation removed. Fig. 9 is 55 a view of the outer or lamp receiving end of

the socket. Fig. 10 is a perspective view of the bridging member of the switch. Fig. 11 is a view similar to Fig. 7, with the socket embodying the different modified form of the invention. Fig. 12 is an inner end view 60 thereof with the cap members of the shell and interior insulation removed. Fig. 13 is an outer end view of the socket. Fig. 14 is a detail of a portion of the switch mechanism. Fig. 15 is a sectional view of a portion of a socket embodying a different slightly modified form of the invention. Fig. 16 is a perspective view of a switch of the pull chain type embodying the invention. Fig. 17 is a longitudinal section thereof, and Fig. 18 is a perspective view of a, 70 slightly modified form of this type of switch.

Referring to the drawings, 1 and 2 designate the base and cap parts, respectively, 75 of the interior insulating body of the sockets herein shown, and 3 and 4 designate the body and cap portions, respectively, of an inclosing shell for the insulating parts of the socket, as is customarily employed in 80 certain types of sockets of the character described. The parts 3 and 4 of the shell are separably secured together in any suitable or convenient manner, as is well understood 85 in the art.

The parts 1 and 2 of the interior body insulation of the socket coöperate, in the present instance, to form a closed, or insulated, 90 closed, chamber 5 in which the switch mechanism is located. The insulating cap 2 and the shell cap 4 have centrally disposed registering openings 6 through which terminal wires 7 may be introduced into said chamber. The cap 2, in the present instance, is provided on its inner side, or interiorly of the chamber 5, with a pair of binding screws 8, which serve to bind the terminal wires 7 to respective contact plates 9 and 10, which are carried by the insulating cap on the inner side thereof. These contact plates, in the present instance, have fingers 11 and 12, respectively, projecting therefrom into the chamber 5 lengthwise of the socket and these fingers, when the insulating parts 1 and 2 are in assembled position, have contact with respective contact fingers 13, 14, which rise within the chamber 5 in substantial parallelism with the fingers 11, 12.

The contact 14, in the present instance, 110

projects from or has electrical connection with the inner end of the customary screw shell 15, which is secured to the outer end of the insulating part 1 and forms the side contact for the lamp, connecting plug, or other attachment, inserted into the socket, as is well understood in the art. The screw shell 15 is insulatingly spaced from the outer end of the shell part 3 by an insulating sleeve 16. The other contact 13 of the set, which is carried by the insulating part 1, is intended to have connection with the usual center contact 17 of the socket through the bridging member of the switch mechanism which forms the present invention.

Referring particularly to the preferred form of my switch mechanism, which is illustrated in Figs. 1 to 6 of the drawings, 18 designates the bridging member of the switch, which is carried for rocking movements within the chamber 5 by a U-shaped chair or bracket 19 secured to the bottom of said chamber. The bridging member 18, in the present instance, comprises two side bars 20, 20 which are connected together adjacent to one end of the bridging member by cross-pieces 21 and 22, the piece 21 being disposed at what may be termed the rear end of the bridging member and the piece 22 being disposed at the fulcrum point of said member. Trunnions or pivot studs 23 project from the ends of the cross-piece 21 through the bars 20, and are journaled in the bearings of the chair 19 and permit a 35 rocking of the bridging member relative to said chair.

The switch illustrated in Figs. 1 to 10 is of the key type and has the exposed key 24, the shaft 25 of which projects inwardly 40 through registering openings provided therefor in the shell part 3 and insulating part 1, and is journaled within the chamber 5 in an upright bearing part 26 which projects upward from the rear end of the chair 19. The shaft 25 after projecting through the bearing standards 26 enters and passes 45 through openings 27 and 28 provided, respectively, in the cross-pieces 21 and 22 of the bridging member. The opening 28 is 50 of circular form while the opening 27 is necessarily of elongated form in the plane of rocking movements of the cross-piece 21 to permit the desired rocking of the bridging member 18 transversely of the shaft 25. In 55 order to prevent rocking movements of the bridging member 18 until the key shaft 25 has been turned a predetermined extent, said shaft, or at least the portion thereof which projects through the opening 27, is flattened 60 in form and said opening is provided with circular end portions of a suitable size to prevent a free turning of the shaft therein, and the portion of the opening intermediate said circular end portion is restricted to a 65 width substantially equal to the width of the

flattened portion of the shaft. It is thus evident that the bridging member 18 may have a rocking movement at each half rotation of the key.

A spring member 29 is carried by the 70 shaft 25 to turn therewith and, in the present instance, is disposed at the outer side of the cross-piece 22. This spring, in the present instance, is of looped form and has its legs straddling the shaft 25 and coiled intermediate their ends about the respective ends of a pin 30, which is carried by the shaft 25 in transverse relation to the flattened surface thereof. The looped end of the spring projects from the point 30 cross-wise of the shaft and bears at its outer end against the outer side of the cross-piece 22 and serves to yieldingly force a rocking of the bridge-member in one direction or the other depending on the edge portion of the cross-piece 22 against which the spring is bearing, as is readily apparent, by reference to Fig. 6. The free ends of the spring legs project forward from the pin 30 and are fixed to the shaft 25 in any suitable or convenient manner.

It is evident that upon a turning of the shaft 25 in either direction the looped end of the spring 29 is revolvably moved about the shaft axis so that its position is successively shifted from adjacent to first one and then the other of opposing side edges of the cross-piece 22, thereby exerting a spring pressure first against one and then against the diametrically opposed edge portion of the cross-piece 22 to impart rocking movements in different directions to the bridging member. It is also evident that the switch is caused to have quick make and break movements, whereby arcing is prevented, by reason of the co-operative action of the elongated opening 27 and the flattened form of the shaft 25 preventing a rocking of the bridging member 18 until each half turning movement of the key has 110 been completed. The holding of the bridging member against rocking until the key has completed a half turning movement causes a storing of considerable energy in the spring due to the inclined relation of the 115 cross-piece 22 to the shaft, thereby causing the spring to impart a quick rocking movement to the bridging member as soon as said member is released for said purpose.

When the bridging member 18 is in one 120 position of its movement the forward or free end of one bar 20 makes contact with a registering portion 13^a of the contact 13 and the forward or free end of the other bar 20 makes contact with a registering part 17^a 125 which either forms a part of or is electrically connected to the center contact 17, as shown in Figs. 2 and 3. When the bridging member is in contact with the contacts 13^a and 17^a it is apparent that a circuit is completed 130

between said contacts through the bridging member, the parts 20, 21 and 22 of said member being of electrical conductive material.

In the modification illustrated in Figs. 7 to 10 the switch mechanism is substantially the same as that above described, except that the position of the bridging mechanism is reversed with respect to the operating key, 10 and the positions of the bridging member pivot and the actuating spring are changed. In this form of the invention 31 designates the side bars of the bridging member; 32 and 33 the inner and outer cross-pieces for said bars, and 34 the actuating spring, which is carried by the key-shaft 25 in the same manner as the spring 29. The outer cross-piece 33 is the one, however, provided with the trunnions 35 which are journaled in the chair 19, and is also the one which receives the thrust of the spring 29, while the inner cross-piece 32 is the one provided with the elongated opening 36, which is similar to the opening 27 of the first described construction and co-operates with the flattened form of the key shaft to control the rocking movements of the bridging member. The operation of this form of the invention is apparent from the foregoing description.

In the form of the invention illustrated in Figs. 11 to 14, which is also of the key type, 40 designates the bridging member of the switch which is pivoted at one end thereof to a chair or bracket member 41 that is secured to the base of the chamber 5 within the insulating body. The free end of the bridging member 40 when in one position of its rocking movement makes contact with and connects the contact parts 13^a and 17^a in circuit with the center contact 17 of the socket the same as in the case of the preferred form of the invention. The member 40 has the parts 42 and 43 rising from opposite side edges thereof in parallel relation, the part 42 being of disk form and having the figure-8 opening 44 in its central portion of similar form to the opening 27 in the preferred form of the switch, and the part 48 being of ring form with the opening thereof preferably of greater diameter than the length of the opening 44, as best shown in Fig. 14. The key shaft 45 projects through the chamber 5 over the bridging member 40 in transverse relation thereto and through the parts 42 and 43 of said member. The shaft 45 is of flattened form to adapt it to pass through the restricted central portion of the opening 44 only when one of the narrow edges of the shaft is in register with such portion. The finger 46 is pivoted to the shaft 45 and projects transversely and lengthwise of the shaft from one narrow edge thereof and into the interior of the ring part 43 of the bridging member. A coiled compression spring 47 is disposed between

the shaft 45 and finger 46 and serves to cause the free end portion of the finger to have a yielding outward bearing against the inner peripheral edge of the ring part 13 whereby to influence a rocking movement of 70 the bridging member 40 in first one direction and then the other as the key is rotated.

It is evident that the shaft 45 and the free end of the spring pressed finger 46 are thrust apart immediately after the shaft has 75 moved from one end portion to the other of the opening 44 and that the spring finger is gradually drawn toward the shaft during the succeeding half rotation thereof so that the shaft and spring finger are the closest 80 together and the spring 46 is compressed the greatest extent when the shaft has completed its half turn, thus causing each half rotation of the shaft to store energy in the spring finger 46 and its spring 47 to impart 85 a rocking movement to the bridging member 40 when a narrow edge of the shaft has moved into register with the restricted central portion of the opening.

The construction shown in Fig. 15 is the 90 same as that last described except that a spring finger 48 is substituted for the pivoted finger 46 and coiled compression spring 47, and the key shaft which is designated 49 is only narrowed at the portion thereof 95 which projects through the figure-8 opening in the part 42. The key shaft in each of Figs. 11, 12 and 15 is journaled at the end thereof adjacent to the key head in a bearing standard 50 and at the opposite end 100 thereof in a bearing standard 51.

It is apparent that in each form of my invention hereinbefore described the bridging member is provided with an opening of figure-8 form which co-operates with a flattened portion of the key shaft to control the rocking, or circuit making and breaking movements of said member, and that the part for actuating the rocking movements of the bridging member is carried by and 105 rotates with the key shaft and acts against the bridging member in such a manner that the energy of said part is restored after each member rocking operation.

In Figs. 16, 17 and 18 are illustrated two 115 forms of the invention embodied in switches of the pull chain type. Referring particularly to Figs. 16 and 17, 60 designates the bridging member of the switch, said member being of U-shape and pivoted at its inner end 120 for rocking movements to spaced upstanding arms 61 of a chair or bracket member 62. The legs of the bridging member 60 are connected adjacent to their inner ends by a cross-piece 63 which is provided with an 125 opening 64, the end walls of which have inwardly projecting lugs 65.

A reciprocating control member or slide 66 projects through the opening 64 in the bridging member and is guided for recipro- 130

4
catory movements by arms 67, which rise in spaced relation from the forward end of the bracket 62, and by an arm 68, which rises from the rear end of said bracket intermediate the arms 61 and is provided with a guide opening 69 through which the slide projects. The slide 66 is provided in its forward end portion with an elongated opening 70 and in each side edge, in the present instance, with a notch 71, which, when moved in register with the respective lug 65, permits a passage of such lug therethrough and a consequent rocking of the bridging member in the desired direction. A spring finger 72 is carried by the bracket 62 and acts on the slide 66 to normally hold it at the limit of its forward movement, in which position the notches 71 stand out of register with the lug 65, as shown in Fig. 16.

20 A plunger 73 projects loosely through an opening 74 in the forward end wall of the opening 70 and has its forward or outer end headed, as at 75, to coact with the forward end of the slide 66 to limit the inward movement of the plunger relative thereto, and has its inner end forked, as at 76, with its arms extending in opposite directions in the plane of rocking movements of the bridging member. A coiled compression spring 77 is mounted on the plunger 73 intermediate the forked end 76 thereof and the outer end wall of the slide opening 70 and serves to normally retain the plunger in the positions indicated in the figures. The rear end of the slide 66 is adapted for attaching to a pull chain or other tension member (not shown).

In the operation of this form of switch the operator effects a rearward movement of the slide part 66 against the tension of the spring finger 72, thus moving the plunger 73 rearward relative to the bridging member and causing one of the fork arms 76 thereof to engage the registering edge portion of the cross-piece 63 of the bridging member, the lower edge of said cross-piece, in the present instance, being engaged, as is apparent by reference to Fig. 17. The plunger now stands still during the continued rearward movement of the slide-part, thus effecting a compression or storing of additional energy in the spring 77. When the slide has been moved rearward a sufficient distance to place the notches 71 therein in register with the lug 65 on the bridging member, said member, in the present instance, is released for downward rocking movements and the pressure of the plunger 73 against the lower edge of the cross-piece 63 effects a quick downward rocking of the bridging member, thereby causing either a making or breaking of the electric circuit in which the switch is disposed, depending on the position of the contacts relative to the bridging member.

65 When the slide 66 has returned to its normal

forward position after a releasing of the pulling tension thereon the plunger 73 frees itself from engagement with the lower edge of the cross-piece 63 and stands in position for the other arm of its forked end to engage the opposite edge of the cross-piece to that previously engaged, whereby the next rearward movement of the slide will cause the plunger to effect an upward rocking movement of the bridging member. It is evident that the opening 64 in the cross-piece 63 is of sufficient width to permit the desired rocking of the bridging member. In order that the rearward movement of the slide 66 may be stopped at the point of register of the lugs 65 and notches 71, the slide is provided with one or more shoulders 78, which coact with the inner or looped end portion of the bridging member for such purpose.

The form of switch illustrated in Fig. 18 is substantially the same as that last described except that the form of the slide or control member and its manner of carrying the actuating plunger is slightly changed. The bracket is also slightly changed to meet the changed form of the slide. In this figure, 80 designates the bridging member; 81 the cross-piece of said member; 82 the control or slide member which projects through the opening 83 in the cross-piece 81 and has a notch 84 through which the lug 85 of the cross-piece passes when the notch and lug are in register; 86 the plunger; 87 the spring carried by the plunger, and 88 the chair or bracket carrying the bridging member and slide. It is not thought necessary to give a more detailed description of this form of the invention, as its operation is the same as that of the pull switch construction last above described.

I wish it understood that while I have particularly described my invention in connection with a socket of a particular construction, I do not thereby intend to limit its use, the embodiments shown being merely for illustrative purposes. It is also to be understood that the invention is not limited to any particular construction and arrangement of the parts but is capable of other modifications in whole or in part from those illustrated without departing from the spirit of the claims.

Having thus described my invention, what I claim as new, and desire to secure by Letters Patent, is,—

1. In a switch of the class described, a bridging member mounted for rocking movements; an operating key for said member, said key and member having interengaging parts which coöperate to positively prevent rocking movements of the member except when the key is at predetermined points in its rotation, and a yielding element carried by the key for rotation therewith and acting on the bridging member to

urge it to have rocking movements when released by said key.

2. In a switch of the class described, a bridging member mounted for rocking movements and having a part spaced from its rocking axis and provided with an elongated opening having circular end portions and a restricted intermediate portion, a key having a narrowed shaft part projecting through said opening for turning movements in the ends of the opening and for movement from one portion to the other of the opening when said narrowed shaft portion is at predetermined points in its turning movement, and means operable to urge the bridging member to have movements in first one direction and then the other relative to the key shaft upon a turning of said shaft.

3. In a switch of the class described, a bridging member mounted for rocking movements and having spaced parts each provided with an opening with one of said openings elongated and restricted at its central portion, a rotatable element projected through said openings and having a portion coacting with said elongated opening to control the rocking movements of said member, and means acting on said member to urge it to have rocking movements in first one and then the opposite direction when said element is rotated.

4. In a switch of the class described, a bridging member mounted for rocking movements, a rotatable element having a part co-operating with a part of said member to control the rocking movements of the member when the element is rotated, and spring means carried bodily by said element for rotation therewith and urging a rocking of said member in first one and then the opposite direction when said element is rotated.

5. In a switch of the class described, a bridging member mounted for rocking movements, a rotatable element projected through a part of said member and co-operating therewith to permit rocking movements thereof only at predetermined points in a rotation of said element, and spring means carried by said element and having a thrust part coacting with said member, said thrust part describing an orbital movement upon a rotating of said element and causing said member to have quick rocking movements when released for such purpose.

6. In a switch of the class described, a bridging member mounted for reciprocal movements to make and break a circuit, a rotatable element projecting through a part of said member, said element and member having parts which coact to prevent movements of the member except at predetermined points in a rotation of said element, and means carried by said element and acting on the member and operable to urge a

movement of the member in the direction of movement for which it is released by the element when at a predetermined point in its rotation.

7. In an electric switch, spaced contacts, an oscillating bridging element for making and breaking connection between said contacts, a control member movable relative to said element, said member and element having parts which co-operate to lock the element against shifting movements until the member has been moved a predetermined extent, and means carried bodily by said member for movements therewith and acting on a part of said element to effect a snap shifting movement to said element at each successive movement of said member to element releasing position.

8. In an electric switch, a bridging element having spaced electrically connected side arms forming contact parts, said element being mounted for rocking movements in a plane at right angles to the plane in which said side arms are spaced and having a cross-bar connecting said side arms in spaced relation to the rocking axis of the element and to the free ends of its side arms, said bar having an opening therethrough lengthwise of said element, a control member movable relative to said element and disposed lengthwise thereof and projected through said bar opening, said member and bar having parts which co-operate to lock the element against rocking movements until the member has been moved a predetermined extent, and means carried by said member and operable to impart snap shifting movements to said element when released for movement by the control member.

9. In an electric switch, a bridging element mounted for rocking movements and having side arms forming contact parts and spaced transversely of the plane of rocking of the element, a pair of bars connecting said arms adjacent to the rocking axis thereof and spaced lengthwise of the element, one at least of said bars forming an electrical connection between the side arms of said element and one bar having an opening therethrough lengthwise of the element, a control member disposed lengthwise of said element and projected through said bar opening for movements relative to the element, said member and bar having parts which co-operate to lock the element against shifting movements until the member has been moved a predetermined extent, and means operable by movements of said member to act against one of said bars to impart snap movements to said element when released for movement by the control member.

10. In an electric switch, a bridging element mounted for rocking movements to make and break an electric circuit, said

- 6
- element having a pair of contact arms spaced transversely of the plane of rocking movements thereof and having a plurality of bars connecting said arms adjacent to the 5 rocking axis thereof, said bars being spaced lengthwise of said arms, a control member disposed lengthwise of said element between the arms thereof and projected through both said bars and movable relative to said 10 element, said member and one of said bars coöperating to lock the element against rocking movements until the member has been moved a predetermined extent, and means energized by a predetermined movement of said member and operable to act on one of said bars at first one side and then the other of the member to impart snap movements to said element when released, for movement by the control member.
11. In an electric switch, a bridging element mounted for rocking movements to make and break an electric circuit and having side contact arms spaced transversely of the plane of rocking of the element and a 15 pair of cross-bars connecting said side arms adjacent to the rocking axis thereof and in spaced relation lengthwise of the element, a rotatable control member projected through said bars lengthwise of the element and co- 20 operating with one of said bars to permit rocking movements of the element only at predetermined points in a rotation of said member, and yielding means carried by said member and acting on one of said bars to 25 impart snap shifting movements to said element in first one direction and then the other when successively released for movement by the control member.
12. In an electric switch, spaced contacts, 30 a bridging element mounted for rocking movements and movable to make and break connection between said contacts, said element having a part projecting therefrom in
- spaced relation to its rocking axis and transverse to its plane of rocking movements, a 45 control member movable relative to said element and disposed lengthwise thereof, said member and element part coöperating to lock the element against rocking movements until the member has been moved a predetermined extent, and means carried by and actuated by movements of said member to store energy therein and to act on said element through its said part to move it first in one direction and then the other when successively released by said member.
13. In a switch of the class described, a bridging member mounted for rocking movements and having spaced parts each provided with an opening, with one of said 50 openings elongated and restricted at its central portion, a control element movably projected through said openings and having a portion coacting with the wall of said elongated opening to control the rocking movements of said member, and means acting on said member to urge it to have rocking movements in first one and then the opposite direction when said element has predetermined movements.
14. In a switch of the class described, a bridging member mounted for rocking movements, a movable control element projected through a part of said member and coöperating therewith to permit rocking movements thereof only at predetermined points in a movement of said element, and spring means carried bodily by said element and having a thrust part coacting with said member, said thrust part causing said member to have quick rocking movements when released for such purpose.

In testimony whereof, I have hereunto signed my name to this specification.

DAVID D. GORDON.
